IRA T. SWARTZ, OF INDIANAPOLIS, INDIANA, ASSIGNOR TO SWARTZ ELECTRIC COMPANY, OF INDIANAPOLIS, INDIANA, A CORPORATION OF INDIANA.

ELECTRIC-CIRCUIT MAKING AND BREAKING DEVICE.

1,357,532.

Specification of Letters Patent. Patented Nov. 2, 1920.

Application filed April 3, 1918. Serial No. 226,516.

To all whom it may concern:

Be it known that I, IRA T. SWARTZ, a citizen of the United States, residing at Indianapolis, Marion county, and State of Indiana, have invented and discovered certain new and useful Improvements in Electric-Circuit Making and Breaking Devices, of which the following is a specification.

My invention relates to circuit making and breaking devices and the object of the invention is to produce a device adapted to successfully make and break a circuit, particularly one employing a high tension current, without the use of wiping metallic contacts.

The invention is of particular advantage in ignition circuits for internal combustion engines, although capable of use for other purposes. When used with engines in an ignition circuit it is designed to take the place of the timer and vibrator and, in connection with suitable high tension current producing means, to enable the magneto to be dispensed with.

The invention is illustrated in connection with the ignition circuit of an internal combustion engine, and is embodied in preferable form in the construction, combination and arrangement hereinafter set forth and illustrated in the accompanying drawings.

In these drawings, Figure 1 is a vertical section partly in side elevation of the invention and partly diagrammatic showing the same applied in the ignition circuit of an internal combustion engine and between said engine and a source of high tension current; Fig. 2 is an end view in elevation showing the face of the rotating disk constituting the principal feature of the invention, and Fig. 3, a similar view of a modified form, and Fig. 4, a similar view of another modified form of said disk; Fig. 5, a view similar to Fig. 3 of another modified form of multiple interrupter and Fig. 6 an edge view of Fig. 5.

Referring to the drawings, 1 indicates a battery, 2 a shaft which may be an engine shaft or a dynamo shaft, where such shaft is a continuation of that of the engine, or the same may be any timer and distributing shaft properly geared to the main engine shaft, 3 a dynamo adapted to serve either as a motor to be driven from the battery or as generator, and 4 indicates a transformer

adapted to step up the voltage of the alternating current. The G indicates the generator element of the dynamo and M the motor element thereof. The particular form of means which may be employed to produce an alternating high tension current forms no part of the present invention and other means of producing such a current may be employed. 6 indicates the cylinder of an internal combustion engine, and 7 a spark plug thereof. A high tension current conductor 8 leads from the transformer to a fixed block of insulating material 9 interposed in that part of the ignition circuit leading directly to the spark plug. The conductor lead terminates in a fixed conducting terminal and current projector 10 which is fixed to the said block opposite a channel or air passage 11 extending entirely through the block. A similar conducting terminal and current receiver 12 is mounted at the opposite end of the passage way 11 and is electrically connected by lead 13 with one of the separated points of the spark plug. The other lead 14 goes back to the source of high tension current.

Mounted on the shaft 2 is a disk 15 composed of non-conducting material, preferably of fibrous substance and the inner circumferential portion of which disk is adapted to rotate through a slot or opening 16 formed in the block 9 which is adapted to interrupt the air passage 11 leading through the block. The disk thus interrupts and breaks the path of the current that may be projected from one high tension electrode or projector to the other high tension electrode or receiver through the channel. Formed in the disk in line with the sector formed by the air passage channel 11 is an opening 17 extending through the body of the disk and constituting a valve opening adapted to register with the channel to permit the projection through the channel of the high tension current from one electrode to the other. This opening is enlarged circumferentially to permit sufficient current waves to pass through the same to give a current strength necessary for the spark. The elongation of this opening is proportioned to the frequency of the wave currents and the rate of revolution of the shaft carrying the interrupter member.

In the operation of the device the engine

having been started by hand, or from the motor driven by the storage battery, a high tension current will be produced in the generating means and carried to the projector electrode 12. The disk 15 is so mounted as to rotate at the same speed as the engine shaft, and in the rotation thereof the high tension current from the projector electrode passes against the non-conducting surface 10 of this disk and is thereby insulated from the receiver electrode until the opening 17 in the disk registers with channel 11 whereupon the current will be projected through the air space and a circuit established 15 through the receiver electrode and the spark plug, and a spark will be created at the spark plug. The disk serves as a timer and may be adjusted circumferentially relatively to the shaft to change the timing.

20 In Fig. 3 is shown a plurality of air channel blocks, one for each spark plug lead, to adapt the construction for a multiple cylinder engine and in this case the disk also serves as a distributing segment or in lieu 25 thereof.

In Fig. 4, in place of the opening or openings at the disk adapted to permit the passage of current, a pin or plug or a series of the same 18, are illustrated. These inserted 30 conductor members are metal of a comparatively low electrical resistance and are adapted to permit the flow of current as in the case of the air space openings.

In Figs. 5 and 6 an arrangement is shown 35 in which the interrupter member instead of a disk, consists of a rotatably driven ring 19, of non-conducting material provided with a localized current conducting area such as an air hole 20 or a metallic member 40 of low electrical resistance. This ring is mounted on a shaft 21. It serves to separate a plurality of fixed inner conductors 22 carried by a fixed boss or hub 23 from an outer series of corresponding fixed conductors 24, 45 adapted to be connected to spark elements or other current receiving means. In the rotation of this ring it interrupts the circuit except at the instants when the conducting point 20 registers with any pair of opposing 50 fixed conductors.

The invention may be used with a magneto, if desired, and in such case will dispense with wiping contacts of the timing mechanism or the high tension current may

be taken directly from the generator without the use of a magneto. 55

With whatever form of high tension current generating means the device may be employed it will be seen that it dispenses with the necessity for the use of wiping, rubbing 60 or spring-pressed metallic contacts intermediate the source of generation of the current and the spark producing element, or other means to which the current is to be directed.

Having thus described my invention, what 65 I claim is:

1. An electric circuit making and breaking device comprising a primary circuit, a secondary circuit including a spark plug, said secondary circuit having a gap therein, 70 terminals formed on either side of said gap, and a non-conductive rotatable member projecting into said gap, but out of contact with said terminals, said member having a relatively conductive portion adapted to aline 75 intermittently with the terminals of the secondary circuit.

2. An electric circuit making and breaking device comprising a primary circuit, a secondary circuit including a spark plug, 80 said secondary circuit having a gap therein, terminals formed on either side of said gap, a non-conductive rotatable member projecting into said gap, said member having a slot adapted to aline intermittently with the terminals of the secondary circuit. 85

3. An electric circuit making and breaking device comprising a primary circuit, a secondary circuit including a spark plug, 90 said secondary circuit having a gap therein, terminals formed on either side of said gap in alinement, and a non-conductive rotatable disk projecting into said gap, said disk having a slot adapted to aline intermittently with the terminals of the secondary circuit, 95 a shaft, said disk being mounted thereon, said shaft being rotated in synchronism with the shaft of an internal combustion engine to correctly time the spark in the cylinder thereof. 100

In witness whereof, I have hereunto set my hand and seal at Indianapolis this 23rd day of March, A. D. nineteen hundred and eighteen.

IRA T. SWARTZ. [L. s.]
